United States Patent Office

Des. 177,374
Patented Apr. 10, 1956

177,374

AIR CONDITIONING UNIT

Lurelle Guild, New York, N. Y., assignor to Carrier Corporation, Syracuse, N. Y., a corporation of Delaware

Application March 10, 1955, Serial No. 34,982

Term of patent 7 years

(Cl. D62—4)

FIG. 1

FIG. 2

Figure 1 is a perspective view of an air conditioning unit embodying my new design; and Figure 2 is a top plan view thereof.

The other side of the air conditioning unit forming the subject of this invention is similar to the side shown.

I claim:

The ornamental design for an air conditioning unit, as shown and described.
